TILTING BARGE

Application filed November 15, 1929, Serial No. 407,521, and in Germany December 24, 1928.

Our invention relates to tilting barges or skutes and more particularly to an improved barge or skute of the stated type having a heeling-over tank and railings or breast walls adapted to be turned out of the way, the main object of our invention is to provide means for locking the railings or breast-walls adapted to be turned down, in a manner that upon opening of the sea-valve or sea-valves for the purpose of causing the barge or skute to heel over or tilt, the said railings or breast-walls will be automatically unlocked, when the barge or skute occupies a certain predetermined inclined or heeled position in the water.

With this object in view the locking means may, for example, be operated, for the unlocking purpose, by the action of gravity inherent to or produced by the heeled-over position of the vessel, and in such a case the locking means may be suitably connected with a pendulum-weight which will normally hold the railing or breast-wall in locked position, but allow the same to turn out and down when the vessel occupies the said inclined or heeled position. In a modified form and arrangement the locking means is positively connected, either immediately or with the aid of suitable intermediate means, with the sea-valve or with any operating part of the sea-valve so that the normally locked parts will be unlocked only when the sea-valve is partially or totally open and the vessel already occupies a predetermined inclined or heeled position in the water.

In the former case where the locking means are operated by gravity or a pendulum-weight, a separate device may be provided for locking or securing the gravity-operated locking means against accidental disengagement and such a safety device may be positively connected with the sea-valve or with any operating part of the sea-valve so as to be actuated by the latter.

The sea-valves are preferably arranged so as to be operable immediately by hand or at a distance, that is from the steam-tug, by means of any appropriate connections.

Accordingly, our invention possesses the advantage of rendering any manual attend-

ance or control of the movable railings or breast-walls unnecessary, while the provision of the said safety device does not permit of unloading the vessel except upon opening the sea-valve or valves. Moreover there is another marked advantage inherent to our invention and which resides in the fact that by controlling the sea-valve or valves from the steam-tug and automatically unlocking the railings or breast-walls, the unloading or discharging operation will be accomplished in an unobjectionable manner and without the necessity of hands on board the barges or skutes, since the post of duty of the crew or hands is exclusively on board the steam-tug.

We shall now proceed to describe our invention more in detail in connection with the embodiment thereof illustrated somewhat diagrammatically on the accompanying drawings, it being understood that the invention is illustrated by, but not limited to the embodiment thereof so illustrated and described.

In the accompanying drawing forming a part of this specification, and showing for purposes of exemplification, a preferred form and manner in which the invention may be embodied and practised:

Figure 1 is a view in elevation of the loaded barge or skute provided with locking means for the tiltable railings or breast-walls, the latter being shown in locked position and the vessel floating in horizontal position, Figure 2 is a similar view with the water-tank on one side filled, the breast-wall on the same side unlocked and tilted over and the vessel in heeled over position with the load discharging. With reference to the drawings, the barge or vessel *a* is of the lowry type and shaped to form a closed box-like rectangular hollow body with a compartment *b* on either side adapted to be filled with water through an opening controlled by a valve *c*, the so-called sea-valve. On the flush-deck *d* railings or breast-walls *e* are provided and adapted to be tilted or turned out and down as usually in transporting vessels of this type. The compartments *b* serve the heeling purpose since it is customary to unload or discharge vessels of this type by allowing the load to glide off from the deck after the vessel has

been caused, by filling a compartment with water, to occupy an inclined or heeled over position in the water, as shown in Figure 2. To this end the valve or valves on the corresponding side are to be opened, while the railing or breast-wall on the same side is still held in upright and locked position.

The means employed for holding the railings or breast-walls in upright position are two-armed hooks *h* pivotally mounted at *f* and adapted to engage over the top edge of the railings or breast-wall, as shown in Figure 1. The lower arm or tail of the hook *h* is equipped with a pendulum-weight *g* which normally holds the hook in engaging position, but which when the vessel occupies the inclined position for the unloading purpose, as shown in Figure 2, will cause the hook to release the railing or breast-wall *e* so that the latter turns outboard and drops into the position shown in Figure 2 and allows the load to glide off the deck.

The hooks *f* may be secured in position and prevented from disengaging from the railing or breast-wall, by a particular locking or safety means such as a bolt *i*, so that the railing or breast-wall cannot turn and drop outboard accidentally or when the vessel is rolling at sea, and means which in themselves are of known construction and arrangement, may be provided for interconnecting the safety or locking means, such as the bolt *i*, with the sea-valve *c* so that the former will be controlled by the latter.

Though we have described with great particularity of detail one practical construction of our present improvements yet it will be apparent that the device is susceptible of embodiment in various alternative forms, and we therefore reserve the right and privilege of resorting to all such legitimate changes as may be fairly embodied within the spirit and scope of the invention as claimed.

What we claim is:—

1. A tilting barge or skute, comprising a closed water tank or tanks for heeling over purposes, side railings or breast-walls pivotally attached to the deck so as to be capable of turning out and down, means for securing or locking the said railings or breast-walls in upright position, a valve-controlled opening in the said tank or tanks, and means for automatically disengaging the said locking means upon the opening of the said valve.

2. A tilting barge or skute, comprising a closed water tank or tanks for heeling over purposes, side railings or breast-walls pivotally connected to the deck so as to be capable of turning out and down, two-armed hooks pivotally disposed so as to lock the said railings or breast-walls in upright position, a valve-controlled opening in the said tank or tanks, and a pendulum-weight attached to the said hook and adjusted to unlock the said hooks upon the opening of the said valve.

3. A tilting barge or skute of the character set forth in claim 1, wherein the said locking means, such as a weight-loaded pivotal hook, is positively connected with the valve, substantially as and for the purpose set forth.

4. A tilting barge or skute of the character set forth in claim 1, wherein a safety device such as a bolt, is provided for holding the locking means in normal or engaging position, the said device being connected with the valve so as to be controlled by the latter, substantially as and for the purpose set forth.

5. A tilting barge or skute of the character set forth in claim 1, wherein means are provided for controlling the valves of the water tanks or compartments from the steam-tug.

In testimony whereof we have signed our names to this specification.

KARL ZICKEROW. 85
CURT WARNATZ.
